UNITED STATES PATENT OFFICE

142,158

DESIGN FOR A RECESSED SPEAKER GRILLE FRAME FOR A RADIO CABINET

Louis J. Wronke, Chicago, Ill., assignor, by mesne assignments, to Belmont Radio Corporation, Chicago, Ill., a corporation of Illinois

Application July 3, 1944, Serial No. 114,288

Term of patent 3½ years

(Cl. D26—1)

To all whom it may concern:

Be it known that I, Louis J. Wronke, a citizen of the United States, residing at Chicago, in the county of Cook and State of Illinois, have invented a new, original, and ornamental Design for a Recessed Speaker Grille Frame for a Radio Cabinet, of which the following is a specification, reference being had to the accompanying drawing, forming part thereof, in which:

Fig. 1 is a front elevational view of a recessed speaker grille frame for a radio cabinet including an inclined dial scale window showing my new design; and

Fig. 2 is a fragmentary sectional view taken on the line 2—2 of Fig. 1.

The characteristic features of my new design are shown in solid lines in the drawing, the dotted lines shown in Figs. 1 and 2 being for illustrative purposes only.

I claim:

The ornamental design for a recessed speaker grille frame for a radio cabinet, substantially as shown and described.

LOUIS J. WRONKE.
